UNITED STATES PATENT OFFICE.

THOMAS D. JONES, OF SYRACUSE, NEW YORK.

SPIKE-TOOTH HARROW.

SPECIFICATION forming part of Letters Patent No. 691,388, dated January 21, 1902.

Application filed August 12, 1901. Serial No. 71,700. (No model.)

To all whom it may concern:

Be it known that I, THOMAS D. JONES, of Syracuse, in the county of Onondaga and State of New York, have invented certain new and useful Spike-Tooth Harrows, of which the following is a specification.

This invention has for its object the production of a spike-tooth harrow which is particularly simple in construction, economical in manufacture, and highly strong, durable, and efficient in use; and to this end it consists in the devices and combinations herein-after set forth and claimed.

Figure 1 is an elevation of a portion of a spike-tooth harrow embodying my invention. Fig. 2 is a vertical sectional view taken on line 2-2, Fig. 1. Fig. 3 is a sectional view, similar to Fig. 2, the spike-tooth being shown in its position assumed when being reversed. Fig. 4 is a sectional view, similar to Fig. 2, of a modified construction of my invention.

My harrow consists of a frame and spike-teeth.

The frame, only a part of which is here illustrated, is composed of a plurality of frame-bars A of any suitable construction, which, as is obvious to those skilled in the art, are normally fixed during the operation of the harrow. Said frame-bars are preferably of round-
ing cross-section, are provided with substantially upright apertures a, and their lower parts are formed with diverging bearing-faces a', having portions thereof generally extended upwardly toward the front and rear sides of the frame-bars.

The spike-teeth B are secured at intervals to the frame-bars A. The lower portions of said teeth are formed with front and rear diverging substantially upright faces b b and their upper portions are provided with shoulders b' and attaching ends or shanks b². Said shoulders b' are integral with the main bodies of the teeth, and extend laterally, forwardly, and rearwardly beyond the underlying portions of the spike-teeth, the forward and rearward parts of the shoulders b' being extended upwardly toward their outer edges and being decreased in width toward their upper portions. The shoulders b' engage and interlock with the bearing-faces a' of the frame-bars A, facilitate the support of the frame-bars by the spike-teeth B, and reduce to a

minimum the liability of bending or breaking of the spike-teeth at the bases of their attaching ends or shanks b². Opposite sides 55 of the shoulders b' are of similar construction when the diverging bearing-faces a' consist of the lower portions of the peripheries of frame-bars of rounding cross-section; but said opposite sides may be of different form 60 when other frame-bars having diverging lower faces are used, as seen in Fig. 4, in which A¹⁰ is a frame-bar substantially U-shaped in cross-section, and B¹⁰ is a spike-tooth having its shoulder b¹⁰ of a shape suitable for en- 65 gaging the lower face of the bar A¹⁰. The attaching ends or shanks b² rise above the shoulders b' in planes substantially coincident with the lengthwise planes of the underlying portions of the teeth B and are arranged in 70 the apertures a. As clearly seen in Fig. 2, the upper extremities of the attaching ends or shanks b² project above the frame-bars A and are provided with nuts b³ adjustable lengthwise thereon toward the upper faces of 75 the frame-bars for securing the teeth in position. Suitable nut-locks b⁴ are interposed between the frame-bars A and the nuts b³ and are provided with arms respectively engaged with said frame-bars and nuts for preventing 80 turning of the nuts.

Spike-teeth of the construction described are readily drop-forged or otherwise manufactured at minimum cost, are easily secured in position, are not readily broken, especially 85 at the bases of their attaching ends, greatly facilitate the support of the harrow-frame owing to the construction of their integral shoulders b' and the close engagement thereof with the diverging bearing-faces a', and 90 may be reversed at will by partly unscrewing the nuts and turning the teeth half-way around.

My harrow will be readily understood upon reference to the foregoing description and the 95 accompanying drawings, and it will be obvious to those skilled in the art that more or less change may be made in the construction and arrangement of its parts without departing from the spirit of my invention.

Having thus fully described my invention, what I claim as new, and desire to secure by Letters Patent, is—

In a spike-tooth harrow, the combination of

a frame-bar having diverging normally lower faces; with a spike-tooth having its upper portion provided with an attaching end passed through the frame-bar, said upper portion being also provided with an integral shoulder extending laterally, forwardly and rearwardly beyond the underlying portion of the spike-tooth, the forward and rearward parts of the shoulder being extended upwardly toward their outer edges and said shoulder being engaged with and substantially closely fitting the diverging normally

lower faces of the frame-bar, substantially as set forth.

In testimony whereof I have hereunto signed my name, in the presence of two attesting witnesses, at Syracuse, in the county of Onondaga, in the State of New York, this 5th day of March, 1901.

THOMAS D. JONES.
